UNITED STATES PATENT OFFICE

2,502,096

MAGNETIC SEPARATOR FOR GRAIN CHUTES

John Kotilinek, Berwyn, Ill., assignor to Prater Pulverizer Company, Chicago, Ill., a corporation of Illinois

Application June 26, 1946, Serial No. 679,501

9 Claims. (Cl. 209—223)

1

This invention relates to a device for separating metallic articles from grain and other edibles, and its principal object is to provide a simple and easily operated separating device for ridding grain and other edibles of metals that may be collected therewith.

It is well known that screws, nails, bolts and other metallic articles find their way into grain and other edibles and must be separated therefrom before the grain or other edibles are run through processing machines, as otherwise such metallic articles are likely to cause serious damage to the machinery.

In accordance with the present invention, magnets are employed to collect the metallic articles, which magnets are mounted on a slide and have magnet plates which cooperate with a scraper to scrape the metallic articles from the magnet plates when the slide is drawn outward. No further effort is required besides drawing the slide outward to remove the metallic articles from the grain.

With these and other objects and advantages in view, this invention consists in the several novel features hereinafter fully set forth and more particularly defined in the appended claims.

The invention is clearly illustrated in the drawings accompanying this specification, in which:

Fig. 1 is a vertical longitudinal section through a grain chute, equipped with a separating device embodying a simple form of the present invention.

Fig. 2 is an enlarged vertical longitudinal section through the separating device and a fragment of the chute;

Fig. 3 is a plan of the separating device detached from the chute and showing the magnet element withdrawn;

Fig. 4 is an under plan of the device with the magnet element in operative position; and

Fig. 5 is a cross-section of the device taken on the line 5—5 of Fig. 3.

Referring to said drawings, the reference character 10 designates a rectangular frame which is interposed in a chute 11. The frame has a rectangular opening 10a in its bottom, below which is a slide 12 which is slidably mounted in guide ways formed by rabbeted cleats 13, secured to the underside of the frame 10 by any suitable means such as bolts and nuts 14.

The slide 12 may comprise angle shaped side members 12a and angle shaped end members 12b welded together at the corners formed by the angle shaped members. Welded to the side members 12a are filler plates 12c, the upper faces

of which are flush with the upper faces of the side and end members 12a, 12b. Resting on the filler plates are magnet plates 16 which, together with the filler plates, close the opening 10a through the frame 10.

A flexible flap 32 is secured to the top member of the chute and rests on the slide. Said flap serves to hold the grain down on the slide. A gate 31 is provided in the chute above the separating device, which gate may be closed to arrest the flow of grain down the chute.

To the under side of the magnet plates are bolted or otherwise fastened several spaced apart permanent magnets 15, to which are secured the spaced apart magnet plates 16, as by bolts and nuts 16a. Secured to and extending up from the end members 10b, 10c of the frame are side frame members 17, 18, to which are bolted or otherwise secured the side boards 19 of the chute. The bottom board of the chute is omitted at the place where the opening 10a in the frame 10 is located. The side frame member 17 is formed with a flange 21, welded or otherwise fastened to the end frame members 10b, and its lower edge acts as a scraper for scraping the metallic articles from the magnet plates. The flange 21 is formed with tongues 26 which project down into the spaces between the magnet plates.

Secured to the upper faces of the side frame members 12a of the slide are non-metallic strips of material 22 of the same width as the width of the magnet plates 16.

The slide is provided with a handle 23 on one edge by means of which the slide may be drawn outwards or pushed back into place. Lugs 24, secured to the under side of the slide, cooperate with stop lugs 25, 25a carried by the cleats 13, to limit the inward and outward movement of the slide.

Projecting down from the side frame member 18 are tongues 26a, which project into the spaces between the magnet plates and close the ends thereof.

Beyond the slide the end member 10c of the frame is formed with an opening 27 normally closed by a trap door 28, having a metal arm 29 welded to a rod 29a, secured to the under side of the trap door and fulcrumed in ears 28a which project down from the frame member 10c. The arm 29 normally extends under one of the magnets 15 and is attracted thereby, whereby the trap door is normally held in its closed position. The arm 29 is provided with a handle 30, which facilitates the opening and closing of the trap door.

The arm normally stands in front of a stop member on one of the magnets, which may comprise one of the bolts and nuts 16^a, and prevents the slide from being drawn outward until the trap door has been opened. When the trap door is opened, any material in the chute above it will discharge through the opening 27 in the frame member 10^c, and this will happen if the attendant has not closed the gate 31 in the chute, which gate must be closed when the magnet plates are to be cleaned.

In operation, the grain or other mobile material flows down the chute and across the frame members 10^b, 10^c, the magnet plates 16, filler plates 12^c, and the trap door 28, and any metallic articles mixed with the material are attracted by the magnet plates and lodge thereon. When it becomes necessary to rid the magnet plates of the collected metallic articles, the gate 31 is closed and the trap door 28 is opened, thereby moving the arm 29 out of the path of the stop member 16^a. The attendant then draws the slide outward as far as it will go, the edge of the flange 21 of the side frame member 17 scraping the metallic articles from the magnet plates, which articles fall through the opening 10^a in the frame when the magnet plates are being moved to the outward limit of their movement. The slide is then pushed back into place and the trap door is closed, thereby again bringing the arm 29 into position to prevent the slide from being drawn outward. During the outward movement of the slide, the tongues 26 have scraped away any collected material in the grooves between the magnet plates. Obviously one or more receptacles (not shown) may be placed under the openings in the frame to collect material discharged through said openings.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. A device for separating metallic articles from grain and other edibles, comprising a frame arranged to be interposed in a chute and having an opening therethrough, an outwardly movable slide slidably supported below said frame in close proximity thereto, magnets carried by said slide, and magnet plates secured to said magnets, side frame members extending up from the plates with the lower edges of one side frame member located in close proximity to the upper face of the magnet plates, and functioning to scrape metallic articles from the magnet plates when the slide is drawn outward.

2. A device for separating metallic articles from grain and the like, comprising a frame arranged to be interposed in a chute and having an opening therethrough, an outwardly movable slide located below said opening, guides for supporting said slide, magnets carried by said slide, magnet plates connected to said magnets, side frame members extending up from said plates, one of which functions as a scraper for said plates, and means to limit the inward and outward movements of the slide.

3. A device for separating metallic articles from grain and the like, comprising a frame arranged to be interposed in a chute and having

an opening therethrough, an outwardly movable slide located below said opening, guides for supporting said slide, magnets carried by said slide, magnet plates connected to said magnets, side frame members extending up from said plates, one of which functions as a scraper for said plates, a projection on one of said magnets, and a swingable arm fulcrumed on said frame, normally standing in front of said projection whereby to prevent the slide from being drawn outward except when the arm is moved away from said projection.

4. A device for separating metallic articles from grain and the like, comprising a frame arranged to be interposed in a chute and having an opening therethrough, an outwardly movable slide located below said opening, guides for supporting said slide, magnets carried by said slide, magnet plates connected to said magnets, side frame members extending up from said plates, one of which functions as a scraper for said plates, a trap door closing an opening in said frame, a projection on one of the magnets, and a swingable metal arm secured to said trap door and fulcrumed on the frame and attracted to the magnet by the latter to stand in front of said projection, and thereby prevent the slide from being drawn outward except when the arm is moved away from the projection.

5. A device for separating metallic articles from grain and other edibles, comprising a frame arranged to be interposed in a chute and having an opening therethrough, an outwardly movable slide slidably supported below said frame in close proximity thereto, magnets carried by said slide, and spaced apart magnet plates bolted to said magnets, filler plates below the spaces between said magnet plates, side frame members extending up from the plates with their lower edges located in close proximity to the upper face of the magnet plates, and functioning to scrape metallic articles from the magnet plates when the slide is drawn outward, at least one of said side frame members having tongues extending down into the spaces between the magnet plates.

6. A device for separating metallic articles from grain and the like, comprising a frame arranged to be interposed in a chute and having an opening therethrough, an outwardly movable slide located below said opening, guides for supporting said slide, magnets carried by said slide, spaced apart magnet plates bolted to said magnets, filler plates below the spaces between the magnet plates, side frame members extending up from said plates, one of which functions as a scraper for said magnet plates and said filler plates, and means to limit the inward and outward movements of the slide.

7. A device for separating metallic articles from grain and the like, comprising a frame arranged to be interposed in a chute and having an opening therethrough, an outwardly movable slide located below said opening, guides for supporting said slide, magnets carried by said slide, magnet plates connected to said magnets, side frame members extending up from said plates, one of which functions as a scraper for said plates, a projection on one of said magnets, a swingable arm fulcrumed on said frame, normally standing in front of said projection whereby to prevent the slide from being drawn outward except when the arm is moved away from said projection, and means to limit the inward and outward movements of the slide.

8. A device for separating metallic articles from grain and the like, comprising a frame arranged to be interposed in a chute and having an opening therethrough, an outwardly movable slide located below said opening, guides for supporting said slide, magnets carried by said slide, magnet plates connected to said magnets, side frame members extending up from said plates, one of which functions as a scraper for said plates, a trap door closing and opening in said frame, a projection on one of the magnets, a swingable metal arm secured to said trap door and fulcrumed on the frame and attracted to the magnet by the latter to stand in front of said projection, and thereby prevent the slide from being drawn outward except when the arm is moved away from the projection, and stop means to limit the inward and outward movements of said slide.

9. In a device for separating metallic articles from loose, non-magnetic material, a carrier adapted to extend across an opening in the bottom wall of a duct through which such material is to be passed, means for supporting said carrier in operative position across such an opening to normally close the latter, said carrier being 20 25 slidable relative to said means in a plane extend-

ing substantially parallel to the plane of said opening, a magnetized member carried by said carrier and movable therewith, said member having a face forming a portion of the material engageable face of said carrier and operative to attract and hold metallic articles in material passing over the same, and a scraper element stationarily related to said carrier supporting means having an edge complementary to said face of said magnetized member and engageable therewith when said carrier is moved to an inoperative position for scraping metallic articles from such face of the magnetized member.
